TROUSER FLY CONSTRUCTION

Louis Markin, Chicago, Ill., assignor to Hook-Flex Corporation, Chicago, Ill., a corporation of Illinois

Application October 19, 1949, Serial No. 122,259

9 Claims. (Cl. 2-234)

1

The main objects of this invention are to provide an improved method and form of construction of a trouser fly; to provide an improved method and form of trouser-fly construction which is sturdier and superior in appearance; to provide an improved method of trouser-fly construction which is so simple in its steps of fabrication that it can be employed in the mass production of trousers and by workmen less skilled than those required for custom tailoring; and to provide an improved method and form of trouser-fly construction especially adapted for use with a slide-fastener of the present-day type.

In the accompanying drawings:

Figure 1 is a plan view showing completed the first major step in this improved method and form of trouser-fly construction wherein a piece of trouser fabric, which is to constitute the inner section of the outer trouser fly, has had stitched thereto one of two temporarily interlocked fastener tapes;

Fig. 2 is a fragmentary view of the upper end of the same showing the second step, that of stitching to the trouser-fly piece of fabric the block of fabric which is to be tucked into and overlie a part of the trouser-fly hook fastener;

Fig. 3 is a similar view illustrating the third step of the process, namely the hook stitched to the trouser-fly piece of fabric;

Fig. 4 is a similar view illustrating the fourth step, namely that of slipping the protective block of fabric into the trouser-fly hook;

Fig. 5 illustrates the next step which involves stitching the inner fly section to the piece of cloth which eventually becomes the outer section of the trouser fly;

Fig. 6 is a transverse sectional view, taken on line 6-6 of Fig. 5;

Fig. 7 which is a view similar to Fig. 5 shows the finished product resulting from turning inside out the two superimposed, stitched pieces of fabric which constitute the completed fly so as to conceal the edges of the fabric outwardly of the seam; and

Fig. 8 is a transverse sectional view, taken on line 8-8 of Fig. 7.

The present trouser fly comprises a piece of fabric 10 serving as the inner section of an outer trouser fly and whereon is stitched a slide fastener tape 11, the hook component 12 of a hook and eye fastener, and a hook-protecting block of fabric 13. The piece of fabric 10 with the attached parts is subsequently stitched in superimposed position on the piece of trouser fabric

2

14 which forms the outer section of the trouser fly.

The piece of trouser fabric 10 is cut approximately as indicated in Fig. 1, more or less square at the one end 10a and with the other end thereof curved and slightly reduced in width. Adjacent the end 10a of the piece of fabric 10 on the outer lateral edge 10b is formed a small V-shaped notch 15 which serves to guide the workman in positioning the slide fastener tape 11 and stitching the block of hook-protecting fabric 13.

The fastener tape 11 and its complementary tape 16 are interlocked and laid on the fabric piece 10 as indicated in Fig. 1, with the upper ends of the fastener tapes extending slightly beyond the guide notch 15. Thereupon the fastener tape 11 is stitched along the lines 9 longitudinally of the fabric piece 10, as indicated in Fig. 1. At the same time a small piece of lining 17 may be stitched to the under side of the piece of fabric 10. This first step is completed by releasing and removing the fastener tape 16 which is to be subsequently attached to the inner trouser fly.

The hook-protecting block of trouser fabric 13 is attached by a line of stitching 18 transversely of the length of said piece of fabric 10, preferably in alignment with the notch 15, after a portion 19 of the fabric block 13 is turned inwardly upon itself, as clearly indicated in Figs. 2-4.

The hook 12 may constitute one component of a hook and eye fastener the eye portion of which (not shown) is attached to the inner trouser fly. The hook 12 has its base 20 formed with an aperture 21 providing a cross bar over which may be laid a line of stitching 22 by which to attach the hook to the fly fabric 10.

Subsequent to securing of the hook 12, the block of fabric 13 is folded outwardly over onto the piece of fabric 10 and tucked under an outer leg 23 of the hook 12, as most clearly indicated in Fig. 4. The apertured base of the hook 12 and the stitching 22 by which the hook is attached to the fabric 10 are thereby completely concealed. Thereupon the piece of fabric 10, with these parts attached, is superimposed upon a piece of fabric 14 which is to form the outer or front section of the trouser fly, and the two pieces are stitched along the end 10a and the outer lateral side edge 10b of the fabric piece 10, as indicated at 24 in Fig. 5. Also the protecting block 13 is stitched to the piece of fabric 10 as indicated at 25, on opposite sides of the hook 12. This preferably would be done before the piece 10 is attached to the piece 14.

In its final finished form, the superimposed

3

stitched fabric pieces 10 and 14, as shown in Fig. 5, are turned inside out so as to conceal the edges beyond the seam 24 between the two fly sections; the hook 12 is thereby brought to exposed position Fig. 7 to permit it, in due course, to engage its eye component attached to the other trouser fly.

Modifications and variations of the construction herein shown and described may be resorted to without departing from the spirit and coverage of the appended claims.

I claim:

1. The improved process of forming a trouser fly which comprises cutting a piece of trouser fabric to the desired shape for the inner section of an outer trouser fly, superimposing thereon a pair of interlocked fastener tapes, stitching one of said tapes to said piece of fabric and then removing the unstitched fastener tape, and then successively superimposing on and stitching to said piece of fabric a hook and a hook-protecting block of fabric between the end of said fastener tape and the adjacent end of said piece of fabric and subsequently folding over said block of fabric under said hook.

2. The improved process of forming a trouser fly which comprises cutting a piece of trouser fabric to the desired shape for the inner section of an outer trouser fly, superimposing thereon a pair of interlocked fastener tapes, stitching one of said tapes to said piece of fabric and then removing the unstitched fastener tape, then successively superimposing on and stitching to said piece of fabric a hook and a hook-protecting block of fabric between the end of said fastener tape and the adjacent end of said piece of fabric and subsequently folding over said block of fabric under said hook, and finally superimposing said piece of fabric on another piece of trouser fabric which is to form the outer section of said trouser fly and stitching said two pieces of fabric together along their ends and their outer lateral edges.

3. The improved process of forming a trouser fly which comprises cutting a piece of trouser fabric to the desired shape for the inner section of an outer trouser fly, superimposing thereon a pair of interlocked fastener tapes, stitching one of said tapes to said piece of fabric and then removing the unstitched fastener tape, superimposing a block of fabric on said piece of trouser fabric over said fastener tape and stitching said fabric block along one of its edges to said piece of fabric transversely of said fastener tape, attaching a hook to said piece of fabric intermediate said block of fabric and the end of said piece of fabric, folding said block of fabric onto said piece of fabric with one edge of the block tucked into said hook; and stitching said piece of fabric in superimposed position on a second piece of trouser fabric which is to constitute the outer section of said trouser fly.

4. The improved process of forming a trouser fly which comprises cutting a piece of trouser fabric to the desired shape for the inner section of an outer trouser fly, superimposing thereon a pair of interlocked fastener tapes, stitching one of said tapes to said piece of fabric and then removing the unstitched fastener tape, superimposing a block of fabric on said piece of trouser fabric over said fastener tape and stitching said fabric block along one of its edges to said piece of fabric transversely to the length of said fastener tape after folding over a portion of said block on a line parallel to said fastener tape stitching,

4

attaching a hook to said piece of fabric intermediate said block of fabric and the end of said piece of fabric, folding said block of fabric onto said piece of fabric with one edge of the block tucked into said hook; and stitching said piece of fabric in superimposed position on a second piece of trouser fabric which is to constitute the outer section of said trouser fly.

5. The improved process of forming a trouser fly which comprises cutting a piece of trouser fabric to the desired shape for the inner section of an outer trouser fly, notching said piece of fabric on one of its lateral edges to indicate the line of attachment for a subsequently-applied block of fabric, superimposing thereon a pair of interlocked fastener tapes, stitching one of said tapes to said piece of fabric and then removing the unstitched fastener tape, superimposing a block of fabric on said piece of trouser fabric over said fastener tape and stitching said fabric block along one of its edges to said piece of fabric transversely to the length of said fastener tape in alignment with said notch after folding over a portion of said block on a line parallel to said one lateral edge of said piece of fabric, attaching a hook to said piece of fabric intermediate said block of fabric and the end of said piece of fabric, folding said block of fabric onto said piece of fabric with one edge of the block tucked into said hook; and stitching said piece of fabric in superimposed position on a second piece of trouser fabric which is to constitute the outer section of said trouser fly.

6. The improved process of forming a trouser fly which comprises cutting a piece of trouser fabric to the desired shape for the inner section of an outer trouser fly, superimposing thereon a pair of interlocked fastener tapes, stitching one of said tapes to said piece of fabric and then removing the unstitched fastener tape, superimposing a block of fabric on said piece of trouser fabric over said fastener tape and stitching said fabric block along one of its edges to said piece of fabric transversely to the length of said fastener tape after folding over a portion of said block on a line parallel to a said fastener tape stitching, attaching a hook to said piece of fabric intermediate said block of fabric and the end of said piece of fabric, folding said block of fabric onto said piece of fabric with one edge of the block tucked into said hook; stitching said piece of fabric in superimposed position on a second piece of trouser fabric which is to constitute the outer section of said trouser fly, and stitching said block of fabric to said first-mentioned piece of fabric along said folded-over edge of said block on opposite sides of said hook.

7. A trouser fly construction comprising a piece of trouser fabric cut to form the inner section of the outer trouser fly, a fastener tape stitched to said piece of trouser fly fabric inwardly of and parallel to the outer lateral edge thereof, a hook having a base and a leg parallel therewith in spaced relation thereto, a stitched connection between the hook base and said piece of trouser fly fabric intermediate the end of the fastener tape and the adjacent top edge of said piece of trouser fly fabric, and a hook-protecting block of fabric stitched along one edge parallel with said adjacent top edge of said piece of trouser fly fabric with a portion of said block adjacent said outer lateral edge of said piece of trouser fly fabric folded over to lie between the leg and base of said hook.

8. A trouser fly construction comprising a piece of trouser fabric cut to form the inner section of the outer trouser fly, a fastener tape stitched to said piece of trouser fly fabric inwardly of and parallel to the outer lateral edge thereof, a hook having a base and a leg parallel therewith in spaced relation thereto, a stitched connection between the hook base and said piece of trouser fly fabric intermediate the end of the fastener tape and the adjacent top edge of said piece of trouser fly fabric, a hook-protecting block of fabric stitched along one edge parallel with said adjacent top edge of said piece of trouser fly fabric with a portion of said block adjacent said outer lateral edge of said piece of trouser fly fabric folded over to lie between the leg and base of said hook, said hook-protecting block of fabric being stitched to said piece of trouser fly fabric on the opposite sides of the said hook, said piece of trouser fly fabric with the aforesaid attached parts being then stitched along its top edge and said outer lateral edge to a second piece of fabric cut to form the outer section of said trouser fly.

9. A trouser fly construction comprising a piece of trouser fabric cut to form the inner section of the outer trouser fly, a fastener tape stitched to said piece of trouser fly fabric inwardly of and parallel to the lateral edge thereof, a hook having a base and a leg parallel therewith in spaced relation thereto, a stitched connection between the hook base and said piece

5 of trouser fly fabric intermediate the end of the fastener tape and the adjacent top edge of said trouser fly fabric, and hook-protecting block of fabric stitched along one edge parallel with said adjacent top edge of said piece of trouser fly fabric with a portion of said block adjacent said outer lateral edge of said piece of trouser fly fabric folded over to lie between the leg and base of said hook, said hook-protecting block of fabric being stitched to said piece of trouser fly fabric on the opposite sides of the said hook, said piece of trouser fly fabric with the aforesaid attached parts being then stitched along its top edge and said outer lateral edge to a second piece of fabric cut to form the outer section of said trouser fly.
